UNITED STATES PATENT OFFICE.

ERNEST E. HEINTZ AND THOMAS P. ARCHER, OF DETROIT, MICHIGAN, ASSIGNORS TO TERNSTEDT MANUFACTURING COMPANY, OF DETROIT, MICHIGAN, A CORPORATION OF MICHIGAN.

WINDOW REGULATOR.

Substitute for application Serial No. 722,659, filed June 27, 1924. This application filed September 5, 1925. Serial No. 54,608.

This application is a substitute for our prior application No. 722,659, filed June 27, 1924.

This invention relates to window regulators and has for its object an improvement in a window regulator of the lever type. Regulators of this type are old, and the objective aimed at by the manufacturer is simplicity in construction so that the production costs may be reduced to a minimum.

This invention has for its object an improvement whereby rattling of the moving parts may be eliminated. A further object is the provision of means whereby the regulator parts may be formed principally of stampings to simplify the construction.

In the drawings:

Fig. 1 is a fragmentary view of a coupe showing in dotted lines the window regulator installation.

Fig. 2 is the elevation of the regulator.

Fig. 3 is an elevation of the regulator as viewed from the other side showing in dotted lines a second position of the regulator or the 25 position of the same when the window is lowered part way.

Fig. 4 is a vertical sectional view taken on the line 4—4 of Fig. 3.

Fig. 5 is a detail showing the connection of the regulator arm to the lower sash bar of the window taken substantially on the line 5—5 of Fig. 3.

Fig. 6 is a detail perspective of the regulator plate.

35 *a* designates the window regulator plate which is a single stamping and which is provided with the struck out cup *b* which is slotted as at *c*, so that a portion of the segmental toothed quadrant *d* may pass therethrough and engage the pinion *e*—the driven member of the clutch mechanism.

The details of the clutch do not form a part of this invention and the details need not be explained. A cup-shaped clutch housing *f* is secured to the regulator plate and houses the clutch parts, and a crank handle *g* is adapted to release the clutch when turned by the operator for actuating the driving pinion *e*.

45 Clutches of many types may be used in this connection, it merely being necessary that effort originating in the window and tending to cause the driven seg-

ment or quadrant to drive the driving pinion *e*, binds the clutch parts contained within the clutch housing and prevents the window 55 from moving. It is only possible to raise or lower the window by turning the crank handle, this turning effort releasing the clutch and enabling the operator to actuate the driving pinion *e*, thereby actuating the segmental quadrant to raise or lower the window.

The toothed regulator quadrant or segment is pivoted to the regulator plate as at *h* and the lever arm *i* is riveted or otherwise 65 secured to the quadrant and is provided at its free end with a roller *j* that engages in the sash bar channel *k* carried by the window. Obviously the rocking of the quadrant by turning the crank handle will cause the window 70 to be raised or lowered.

Fig. 6 shows the construction of the window regulator plate which is provided with the punched-out lip or ear *m* which is offset in a plane slightly removed from the plane 75 of the regulator plate. The toothed regulator quadrant when assembled to the regulator plate is adapted to be fitted under this offset ear. Carried by this offset ear is a punched-in depression or boss or point *n* 80 which is adapted to frictionally engage the exposed side of the regulator quadrant. Also the punched-out depression or boss or point *o* in the main body of the regulator plate is arranged in such a manner as to frictionally engage the underside of the regulator quadrant. This is quite clearly shown in Fig. 4. These frictional bosses or points 85 will frictionally engage the regulator quadrant and prevent the quadrant from rattling or vibrating between the plate and the offset ear. This provides a regulator construction which eliminates the rattling of the moving parts, as any unnecessary rattling is quite annoying to the automobile owner, yet the amount of friction is very small due to the small surface.

At the bottom edge of the regulator plate the projection *p* is bent up as shown clearly in Figs. 2 and 4. The regulator quadrant 100 is secured to the stud *q*, said stud being rotatably supported in the regulator plate and provided with a slot *r*. A counterbalancing spring *s* has one end engaged in this slot car-

ried by the stud and the other end looped about the stationary bent up projection or ear p carried by the regulator plate. A movement of the regulator quadrant which lowers the window winds up this counterbalancing spring so that the operator when turning the handle to raise the window is assisted in doing so by the energy stored up in the counterbalancing spring. This projection or ear p cheapens the construction of the regulator, as the plate is formed of a stamping and may be entirely formed by one punch press operation.

Another very important function of the guiding points or bosses is that the same properly guides the stamped metal quadrant with respect to the teeth of the pinion. This is quite important for the reason that very often the regulator parts become bent or distorted by the workman in making the installation. These points serve as an accurate guide to line up the teeth of the quadrant with the relatively narrow teeth of the pinion so that they will always mesh.

25 Riveted or otherwise secured to the end of the clutch cup f is an interiorly threaded adapter bushing u . This is arranged to receive the escutcheon thimble x which can be turned into it and thereby supports the escutcheon plate y . The thimble x is rotatably but permanently secured to the hub of the crank handle by spinning over the end of the hub as at the point z . This forms a handle assembly which can be easily 30 coupled up with the regulator by simply fitting the hub over the projecting shaft l and turning the thimble down into the adapter bushing.

What we claim is:

40 1. In a window regulator, the combination of a regulator plate formed of a stamping, and a regulator segment supported thereby, said regulator plate having one or more points stamped therein which are adapted to frictionally engage the regulator segment.

45 2. In a window regulator, the combination of a regulator plate, and a regulator segment supported thereby, said plate provided with an ear struck out from said plate and offset therefrom whereby the segment may be engaged between the said ear and the main body portion of the plate for the purpose of guiding the outer edges of said regulator segment.

50 5. In a window regulator, the combination, of a regulator plate, and a regulator segment supported thereby, said plate provided with a struck out ear offset from the plane of the plate to provide a guide for the outer portion of said segment, said ear provided with a pressed-in boss for frictionally engaging the said segment.

55 4. In a window regulator, the combination of a regulator plate, and a regulator segment supported thereby, said plate pro-

vided with a struck-out ear offset from the plane of the plate to provide a guide for the outer portion of said segment, said ear provided with a pressed-in boss for frictionally engaging the said segment and the plate 70 provided with a punched-out boss for frictionally engaging the other side of the segment.

5. In a window regulating mechanism, a sheet metal plate, a driven gear carried by 75 the plate in engagement with one side thereof, and for rotary movements relative thereto, said plate having an integral offset portion forming a pinion housing and a tongue which frictionally coacts with the rim portion of the gear in opposition to the plate to brace the gear against lateral movements, a shaft journaled in the offset portion of the plate, a pinion carried by the shaft within the offset portion of the plate and in driving 80 mesh with the gear, and means in fixed relation to the plate forming another bearing for the shaft.

6. In a window regulating mechanism, a plate, a driven gear, a drive pinion meshing 85 with said gear, a shaft for said pinion, and a flexible tongue offset from said plate approximately the thickness of said pinion and forming a bearing for said shaft, and a portion of said tongue frictionally engaging 90 said gear thereby to hold the gear against lateral displacement.

7. In a window regulating mechanism, a plate, a driven gear mounted for rotation 95 on the plate, a drive pinion meshing with 100 said gear, a shaft for said pinion, and an offset portion on said plate forming a bearing for said shaft, said portion being of substantially the thickness of the pinion and providing an integral tongue frictionally 105 to engage said gear for holding the gear against lateral displacement.

8. In a window regulating mechanism, a plate, a driven gear mounted for rotation 110 on the plate, a drive pinion meshing with said gear, a shaft for said pinion, an offset portion on said plate forming a bearing for said shaft, said portion being of substantially the thickness of the pinion and providing an integral tongue, and a detent on 115 the end portion of said tongue frictionally to engage the surface of said gear for holding the gear against lateral displacement.

9. In a window regulator mechanism, a sheet metal plate, a driven gear carried by 120 the plate in engagement with one side thereof, and for rotary movements relative thereto, said plate carrying an offset member 125 forming a pinion housing and having a portion which frictionally co-acts with the rim portion of the gear in opposition to the plate to brace the gear against lateral movements, a shaft journaled in the offset member carried by the plate, a pinion carried by the shaft within the offset member and in driv- 130

- ing mesh with the gear, and means in fixed relation to the plate and forming another bearing for the shaft.
10. In a window regulating mechanism, a plate, a driven gear mounted for rotation on the plate, a drive pinion meshing with said gear, a shaft for said pinion and an offset member on said plate forming a bearing for said shaft, said member having a part spaced from the said plate substantially the thickness of the pinion and providing a portion frictionally to engage said gear for holding the gear against lateral displacement.
11. In a window regulating mechanism, a plate, a driven gear mounted for rotation on the plate, a drive pinion meshing with said gear, a shaft for said pinion, an offset member on said plate forming a bearing for said shaft, said member having a part spaced from the plate substantially the thickness of the pinion and providing a surface for lying along side of said pinion while a surface of said plate lies along the other side of said pinion, and a detent in one of said surfaces to engage the surface of said gear and prevent its moving away from the said surface that lies on the other side of the gear.
12. In a window regulating mechanism, a plate, a driven gear mounted on one side of said plate to rotate thereon, a drive pinion supported to rotate said gear by meshing therewith, a member carried by said plate arranged to lie immediately along the outside surface of said gear adjacent said pinion to hold the said gear and pinion in mesh, one of the members (plate and said member carried by plate) having a punched-out portion which engages the side of the gear and holds said gear up against the other member.
13. In a window regulating mechanism, a plate, a driven gear, a drive pinion meshing with said gear, a shaft for said pinion, said plate carrying a member having a portion off-set from the plate and forming a bearing for said shaft, and a portion of said member spaced from the plate to engage said gear for holding the gear against lateral displaced movement.
14. A unitary window regulator assembly comprising in combination, a plate, a relatively large sheet metal driven gear segment carried by the plate in engagement with one side thereof, a drive pinion, shafts for said gear and pinion spaced to cause meshing of the teeth thereof, and a member carried by said plate having a portion positioned to lie immediately over the outside surface of said gear and pinion where they mesh to retain the teeth in co-acting relation and prevent rattling of the moving parts.
15. A unitary window regulator assembly comprising in combination, a plate, a relatively large sheet metal driven gear segment with stamped out teeth carried by the plate in engagement with one side thereof, a drive pinion, shafts for said gear and pinion spaced to cause meshing of the teeth thereof, and means carried by said plate positioned to lie immediately over and contacting with the outside surface of said gear adjacent said pinion and within the vicinity of the point of contact of the teeth of the gear and pinion to hold the teeth in co-acting relation in the same plane.
16. In a window regulator, the combination with a mounting plate, of a gear segment pivoted upon said mounting plate, a lifter arm connected to said segment and adapted to be operatively connected to a window, a gear member upon said mounting plate meshing with said gear segment, and a struck out tongue upon said mounting plate and engaging the side of said gear segment opposite that engaged by said mounting plate.

In testimony whereof we have affixed our signatures.

ERNEST E. HEINTZ.
